UNITED STATES PATENT OFFICE

2,085,427

TREADLE MECHANISM

Harold Ernest Elliott, Leicester, England, assignor to United Shoe Machinery Corporation, Paterson, N. J., a corporation of New Jersey

Original application May 20, 1935, Serial No. 22,302. Divided and this application December 6, 1935, Serial No. 53,250. In Great Britain July 13, 1934

6 Claims. (Cl. 74—518)

My invention relates to treadle mechanism of a character which may be employed advantageously in, for example, sole-rounding machines. Such a rounding apparatus is disclosed in Letters Patent of the United States No. 882,009, Mayo, March 17, 1908. The present case is a division of an application filed in the names of Joseph Gouldbourn and Harold E. Elliott in the United States Patent Office on May 20, 1935, for 10 improvements in Rounding machines, it bearing the Serial No. 22,302.

Machines of the class above mentioned usually have a treadle-operated mechanism, to be utilized for moving a clamping member into engagement 15 with an article on a pattern, and in some machines it is necessary for the operator to hold the treadle depressed during the operation of the machine with a pressure sufficient to resist movement of the article during rounding. The treadle 20 mechanism has in some instances been so arranged that considerable movement of the treadle has been needed for the initial clamping. This has necessitated a corresponding raising and lowering of the operator's foot, and the pressure 25 required on the treadle has called for undesirable exertion.

It is an object of the present invention to enable the operator to move a clamp or other member to be actuated into engagement with 30 the work by a comparatively small movement of his foot on the treadle, and to effectively clamp the article on the pattern and hold it during the operation of the machine without undue effort. To this end, I associate with the member to be 35 actuated, which may herein be considered as a rod or other element through which force is transmitted, a toggle and a treadle, together with connections by which the toggle may be moved from the treadle either bodily or may be straightened. In the first instance, the treadle movement 40 produces rapid travel of the actuated element for a relatively small treadle-displacement. In the second, the leverage is increased to apply a comparatively heavy pressure while minimizing the effort required on the part of the operator. During 45 the latter effect, the treadle, which is preferably sectional, has a portion locked and its locking may be controlled by a section of the treadle itself, which also may be joined to the 50 toggle to straighten it.

In the drawing,

Fig. 1 is a side elevation, partly in section, of one form of my improved treadle mechanism, and Fig. 2 is a sectional elevation on the line II—II 55 of Fig. 1.

I have shown herein, a two-part treadle-lever pivoted on a horizontal shaft 151 extending across a bracket 153 secured to the frame of the machine in which the mechanism is employed. The front section 155 of the lever is arranged to be 5 depressed by the operator, and the rear section 157 is connected, through mechanism hereinafter described, to a rod 158 joined to the element of the apparatus to be controlled, as the work-clamp of a rounding machine. The sections of the 10 treadle-lever have co-operating stop-faces 161, normally held in contact by a spring 163 joining the treadle-sections but which may be separated by depression of the front section. The rear end of the section 157 has pivotally connected to it 15 the lower extremity of a pair of upwardly extending toggle-links 165, 167. The upper end of the toggle-link 167 is joined to the central portion of a lever 169 fulcrumed at 171 on the bracket 153 and guided by a fork 193 rising from said bracket. 20 To the free end of the lever the rod 158 is connected. The relation of the lever-arms is such that a comparatively small movement of the operator's foot carries the element actuated by the rod 158 through its operating stroke. The rod 25 158 is formed in two parts, there being a spring 173 between them to provide a yielding link joining the toggle and the clamp. The center 179 of the toggle 165, 167 is connected by a forwardly extending link 175 to an arm 177 projecting upwardly from the inner extremity of the section 155 of the treadle-lever. When the front 30 part 155 of the treadle-lever is raised, the toggle is broken rearwardly by the spring 163 acting through the link. The rear of the treadle-section 157 has pivoted on it a pair of depending pawls 181, 181 arranged to engage the teeth of a ratchet-block 183 secured on the bracket 153. The pawls are of unequal length, so that when one of them 35 is in engagement with a tooth of the block the other is engaging the block half way between two adjacent teeth. The teeth of the ratchet-block are so disposed that, when one of the pawls is in engagement with them, the rear of the treadle-lever is locked against downward movement. The 40 pawls are moved by spring-plungers 185 into engagement with the ratchet-teeth, and have upwardly projecting arms 187 for engagement with an adjustable screw 189 projecting horizontally through a lug 191 on the under side of the link 45 175. When the treadle is raised and the toggle is broken, the pawls are held clear of the ratchet-teeth by the screw. 50

When the treadle is depressed, its two sections move about their pivot 151 together, the spring 55

163 connecting them being sufficiently strong to overcome the resistance initially encountered by the rod 158 in bringing the controlled clamp into contact with the work. At this time, the toggle 5 is moved bodily, the angular relation between its links 165 and 167 not being altered. Upon engagement with the work of the member actuated by the rod 158, upward movement of the rear end of the section 151 of the treadle-lever is resisted, and further depression causes the section 155 to swing on its pivot 151 relatively to the rear part. During this movement, the link 175 10 is shifted forwardly, and the screw 189 in the link moves away from the arms 187 on the pawls 15 and allows one of the pawls to engage the ratchet 183. Downward movement of the rear of section 157 is thus resisted during continued depression of the section 155. When this occurs, the link 175 straightens the toggle 165, 167 and 15 work-clamping pressure is applied through the leverage thereof to the rod 158. The spring 173 20 between the two parts of the rod is compressed during the straightening of the toggle, and this spring exerts the clamping pressure. Therefore, 25 this pressure is always substantially uniform for different work-thicknesses, since the combined movement of the two parts of the treadle-lever measures the thickness of the material, and the subsequent straightening of the toggle always compresses the spring 173 by about the same amount. The straightening of the toggle to apply 30 the clamping pressure requires no undue exertion on the part of the operator, and the effort required by the operator to keep the toggle 35 straightened during the operation of the machine is only that needed to overcome the tension of the spring 163. When the operator releases the treadle, the spring 163 raises the section 155 of the treadle-lever and breaks the toggle, thereby 40 relieving the pressure of the clamp on the work-piece operated upon. Toward the end of the upward movement of the lever-section 155, after the toggle has been broken, the pawls are withdrawn from the ratchet-block 183 by engagement 45 of the screw 189, and the rod 158 is lowered by an unillustrated spring, lowering the rear end of the treadle, the sections of which now move together.

Having thus described my invention, what I 50 claim as new and desire to secure by Letters Patent of the United States is:

1. The combination with a work-clamping member to be actuated, of actuating connections

therefor including a toggle which is normally broken, a treadle, connections between the treadle and toggle to move said toggle bodily and thereby produce contact of the member with the work, and other connections between the treadle and toggle to straighten said toggle to apply clamping pressure to the work. 5

2. The combination with a member to be actuated, of actuating connections therefor including a toggle which is normally broken, a treadle, connections between the treadle and toggle to move said toggle bodily, other connections between the treadle and toggle to straighten said toggle, and means for locking a portion of the treadle against movement in one direction during the straightening of the toggle. 10

3. The combination with a member to be actuated, of actuating connections therefor including a toggle which is normally broken, a treadle, connections between the treadle and toggle to move said toggle bodily, other connections between the treadle and toggle to straighten said toggle, and means for locking a portion of the treadle against movement in one direction during the straightening of the toggle and controlled by said treadle. 20

4. The combination with a connecting rod, of a treadle having two sections one of which is yieldable upon the other, a toggle joined at its extremities to said other section and to the connecting rod, a link uniting the yieldable section of the treadle to the center of the toggle, and a spring connecting the treadle-sections to hold them in their normal relation and to permit their yield, said spring maintaining the toggle normally broken. 30

5. The combination with a connecting rod, of a treadle having two sections one of which is yieldable upon the other, a toggle joined at its extremities to said other section and to the connecting rod, a detent for locking said other section against movement, and a link uniting the yieldable section of the treadle to the center of the toggle and acting upon the detent to release the treadle-section. 40

6. The combination with a connecting rod, of a lever fulcrumed at a fixed point and pivoted at its opposite extremity to the connecting rod, a treadle having two sections one of which is yieldable upon the other, a toggle interposed between said other section and the lever, and a link uniting the yieldable section to the center of the toggle. 45

HAROLD ERNEST ELLIOTT.
